UNITED STATES PATENT OFFICE.

JOHN JOSEPH FAGAN, OF JERSEY CITY, NEW JERSEY.

SEWER-BASIN HEAD.

Application filed March 7, 1923. Serial No. 623,472.

To all whom it may concern:

Be it known that I, JOHN J. FAGAN, a citizen of the United States, and a resident of Jersey City, in the county of Hudson and State of New Jersey, have invented new and useful Improvements in Sewer-Basin Heads, of which the following is a full, clear, and exact description.

This invention relates to sewer basin heads. The general object of this invention is the provision of a simply constructed basin head including a main body section and a curb section loosely mounted in the body section interlocking with the members provided on the latter so that the curb section may be detached from the main body section.

This object is accomplished by providing a body section having an opening therein and presenting vertical side walls defining the opening, forming on the vertical side walls flanges on which the curb section may be slidably mounted, providing on the flanges pins for engaging the curb section, attaching it to the body section when the former is in position and utilizing the grate for retaining the curb section in position.

This and other objects of the invention will be more clearly understood from the following detailed description and accompanying drawings.

Figure 1 is a top plan view of the sewer basin head assembled;

Figure 2 is a vertical section along the line 2-2, Figure 1;

Figure 3 is a vertical section along the line 3-3, Figure 2.

Referring to the above-mentioned drawings, the invention includes a body section 10 consisting of an annular plate 11 supporting vertical walls 12 defining an opening 13. Formed on the vertical walls defining the front section of the opening is an inwardly projecting flange 14. Two short flanges 15 are provided on the side walls in alignment with the flange 14 and located near the rear of the opening 13. A plate 16 is formed integral with the vertical walls at the rear of the opening and extends over a portion of the opening, the top of the plate 16 being in alignment with the top of the vertical walls 12. As shown in Figure 2, the flanges 15 overlap the plate 16 and are spaced below the same. Formed on the forward ends of the flanges 15 and projecting forward in a horizontal plane are pins 17. The ends of the

pins 17 do not project forward to the ends of the flange 14 but are spaced therefrom a desired distance. In order to increase the strength of the body 10 webs 18 are formed integral with the annular plate 11 and the vertical walls 12.

As shown in Figure 2, the body 10 is placed on a foundation 19, defining the opening leading into the sewer, the tops of the vertical walls of the body being positioned in alignment with the surface of the street 20. The inner section of the body extends beneath the sidewalk 21, locating the flanges 15 beneath the edge of the sidewalk or a curb.

A curb section 23 for mounting in the rear section of the opening 13 adjacent the plate 16 is provided. This curb section somewhat resembles an inverted box in shape, presenting a rear wall 24, a front wall 25 and two end walls 26. The front wall is deeper than the end walls and has formed on its lower edge a flange 27 for projecting between the flanges 15 and the plate 16 when the curb section is in position. The rear wall slopes away from the vertical as it progresses towards the flange portion. The over-all height of this wall is equal to the distance from the tops of the flanges 15 to the top of the sidewalk 21. The front wall 25 is cut away at 29, forming two depending arms 30 which extend below the flanges 15. Openings 28 are provided in the depending arms 30 in alignment with the pins 17 for receiving the latter to attach the curb section to the body when in position. In mounting the curb section in position the flange 27 is moved along the flanges 15, projecting it between the flanges 15 and the plate 16. The end walls 26 seat on the vertical walls 12, and the openings 28 in the arms 30 receive the pins 17.

The front wall 25 of the curb section lies flush with the outer wall of the curb or sidewalk 21. A grating 31 is then mounted in the front section of the opening 13 seating on the flange 14. This grating 31 serves to retain the curb section 23 in position.

From the above it will be seen that a sewer basin head has been provided including a curb section which interlocks with members provided on the body section of the basin head. This curb section is retained in position by means of the grating 31. In order to remove the curb section 23 for replacement it is only necessary to remove the grating 31.

and draw the curb section outward, disengaging it from the members provided on the body 10.

I would state in conclusion that while the illustrated example constitutes a practical embodiment of my invention, I do not limit myself strictly to the exact details herein illustrated since manifestly the same will be considerably varied without departing from the spirit of the invention as defined in the appended claims.

Claims:

1. A sewer basin head, comprising a body having an opening therethrough, said body 15 presenting walls defining the opening, a cover extending over the rear section of the opening, supporting members carried by said walls and extending inward, a curb section provided with a rearwardly extending 20 flange mounted on the supporting members, said flange projecting beneath the cover over the rear section of the opening, and a grating for mounting in the front section of the opening, said grating serving to fix the 25 curb section in position in the body.

2. In a sewer basin head, comprising a body having an opening extending therethrough, said body presenting walls defining the opening, supports formed on said 30 walls and extending inward, a curb section provided with a rearwardly extending flange for mounting on said supports, means provided on the supports for positively engaging the curb section, means carried by the 35 body for seating over said curb flange when the curb section is in position in the body, and a grating for mounting in said body in front of the curb section, said grating serving to lock the curb section against movement in the body.

3. A sewer basin head, comprising a body having an opening therethrough, said body presenting vertical walls defining the opening, a cover extending over a portion of the

opening at the rear of the body, flanges 45 formed on the vertical walls and projecting inwardly, a curb section formed with a flange integral with its rear wall and extending outward, said curb section being mounted adjacent said cover resting on the 50 flanges provided on the vertical walls, the curb section flange projecting beneath the cover, and a grating mounted in the front section of the opening resting on the flanges provided on the vertical walls, said grating 55 serving to retain the curb section in position.

4. A sewer basin head, comprising a body having an opening extending therethrough, said body presenting vertical walls defining 60 the opening, a plate formed on the body and extending over a portion of the rear section of said opening, flanges formed on the vertical walls and projecting inward, a curb section having an outwardly projecting flange formed on the lower edge of its 65 rear wall for mounting in the rear section of said opening on the body flanges, the curb flange projecting beneath the plate extending over the rear section of the opening, 70 means for fastening said curb section to the body flanges, and a grating for mounting on the body flanges in the front section of the opening, said grating serving to retain the curb section in position. 75

5. A sewer basin head, comprising a body having an opening extending therethrough, said body presenting vertical walls defining said opening, flanges formed on the inner faces of said vertical walls, the flanges 80 at the rear section of said opening being provided with pin members, a curb section for mounting on said flanges in the rear section of said opening, the front wall of said curb section being provided with openings for receiving the pin members provided on the flanges to attach the curb section in position. 85

JOHN JOSEPH FAGAN,
